UNITED STATES PATENT OFFICE.

HUGH MISCAMPBELL, OF DULUTH, MINNESOTA.

LIME-HYDRATING APPARATUS.

Application filed January 17, 1920. Serial No. 352,014.

To all whom it may concern:

Be it known that I, HUGH MISCAMPBELL, a citizen of the United States, residing at Duluth, in the county of St. Louis and State of Minnesota, have invented certain new and useful Improvements in Lime-Hydrating Apparatus, of which the following is a specification.

This invention relates to a mixing apparatus, and more particularly to apparatus for hydrating and mixing lime. The heretofore known types of lime hydrators possess very objectionable features, in that large quantities of lime dust escapes to the outside of the mixing machine, and especially so when dumping the contents of the mixer. Also after it is thoroughly dried, the draft takes a quantity of the hydrate up the stack and scatters it over the surrounding neighborhood, which makes it bad for such hydrating plants to be located within the city limits or close proximity to dwellings, owing to the very disagreeable nature and damaging effects of such dust. In fact, this objection of escaping dust, has prevented the installation of hydrators in various cities. Other objections in the old form of hydrator are its limited capacity, and its lack of thorough mixing before leaving the machine. These objections, together with others not enumerated, are entirely overcome in my improved hydrator forming the subject matter of the present invention.

Among the objects of my invention is to eliminate the escape and scattering of dust outside of the hydrating apparatus; further to greatly increase the capacity and output of such apparatus; further to effect a more thorough mixing and cooling of the material being treated before leaving the machine; further to provide such a combination and arrangement of parts that the material and water can be added at one end, and bagged or conveyed to the bagging place from the other; and such further objects, advantages and capabilities as will later more fully appear.

To the attainment of these ends, and the accomplishment of other new and useful objects, as will appear, my invention consists in the features of novelty in the construction, combination and arrangement of the several parts hereinafter more fully described, and shown in the accompanying drawings illus-

trating an embodiment of my invention, and in which—

Fig. 1 is an elevation broken away in parts for the sake of clearness, showing an apparatus embodying my invention.

Fig. 2 is a vertical longitudinal section through the secondary mixing device.

Fig. 3 is a vertical transverse section through the secondary mixing device on line 3—3 of Fig. 2.

Fig. 4 is a section on lines 4—4 of Fig. 2. It has been found that to more successfully complete the operation of hydration, it is necessary that the material be subjected to long and proper mixing. It is further of great advantage and importance to cool the hydrate to a certain extent before bagging the same, and it is also necessary to the successful operation of this type of apparatus that the product be conveyed from the hydrator outlet to the bagging apparatus. It would not be feasible to carry out this extended mixing and cooling in the heretofore known types of hydrator, since to do so would require not only an apparatus of excessive size, but also a prohibitive number of such hydrators. In my improved hydrator I have combined all of these very desirable features, and have provided an apparatus which combines the operations of finishing the hydration, sufficiently cooling the same, and conveying the product to the delivery outlet, all in one device. At the same time my apparatus enables the doubling or more than doubling of the capacity of this class of machines.

Referring to the drawings, and more particularly to Fig. 1, it will be seen that my improved apparatus comprises the main or primary mixing device P, for the interior construction and arrangement of stirring devices, of which reference is had to United States Letters Patent No. 801,329, issued to me October 10, 1905. The mixing apparatus or chamber P is provided with a suitable stack 1, and the weighing and charging apparatus 2, which as shown is suitably connected to scales 3 for weighing the material to be charged into the primary mixer. There is also provided a source of water supply 3^a, and suitable sprinkling or discharging pipes 4, which latter are positioned within the mixing chamber, and are of any suitable form of construction for adding a desired

quantity of water to the lime being treated. Suitable driving mechanism 5 is provided for rotating the mixer, and the operation and control of the interior stirring devices may 5 readily be effected from the exterior by control mechanism 6.

The mechanism thus far described may be suitably mounted on girders or other supporting members 7, on the level of floor 7^a.

- 10 Below the mixing device P, and suitably secured thereto, is the hopper or bin 8, which is provided at its lower end with a feeding device 9, the function of which is to feed the material being treated from the lower part 15 of hopper 8, into chute 10, from which it passes into the secondary mixing device S, also referred to hereinafter as a combined mixer and conveyer; it being understood, of course, that the amount of material fed into 20 the secondary mixer S may be controlled as desired by feeder 9.

Referring now to the construction of the secondary mixer or combined mixer and conveyer S, it will be seen from Fig. 2 that the 25 same comprises an elongated drum 11, preferably cylindrical in cross section, and having secured to the inner face of its cylindrical shell, the helical flights 12, which as shown, extend substantially the full length 30 of drum 11, and are in width of a dimension less than the radius of the drum. The drum 11 is provided adjacent each end thereof, and secured thereto, with the annular flanges 13, each having a flat outer 35 periphery 14 to serve as a trackway for movement over the rollers 15, rotatably mounted in a suitable frame 16, and which arrangement, as will be readily understood, permits rotation of drum 11 upon rollers 40 15 when suitable power is applied thereto. Also secured upon the exterior of drum 11, is the flange 17, carrying gear teeth 18, adapted to be rotated by pinion 19, carried on shaft 20, rotated by a train of gear 45 mechanism, comprising gear 21, secured upon shaft 20, and meshing with pinion 22 fixed on shaft 23, which shaft also carries belt pulley 24 for operation by a belt, or other suitable means for connecting the same 50 to a source of motive power. It is to be understood, of course, that the frame members 16, and the train of gear mechanism for operating toothed flange 17, are suitably mounted upon appropriate foundation construction or supports, to hold the same in 55 operative position with relation to the drum. Longitudinal movement of drum 11 is prevented by the rollers 25 and 26 rotating in a horizontal plane and contacting with the 60 opposite vertical sides of one of the annular flanges or trackways 13. The end 27 of drum 11, has an aperture 28 therein, through which is adapted to extend the discharge spout 29 of the chute 10, leading 65 from feeder 9. Encircling end 29 and con-

tacting with end 27 of the drum, is a suitable disc or closure 30, to prevent the escape of dust, and the like, from the interior of drum 11. The end 31 of the drum is open, and passes through an opening in a closely fitting sealing member 32 covering an opening in casing 33, which serves as a delivery chute to suitable elevator mechanism (not shown in detail) mounted in the elevator casing 34, and which elevator serves, in case it is not desired to bag the hydrated material at the end of drum 11, to convey the same to any suitable bagging mechanism at a more or less removed position.

In the operation of my improved apparatus, the lime is fed into the primary mixing device P, from hopper 2, and a suitable amount of water added thereto through the sprinkling pipe 4. The primary mixing device P is then rotated by driving mechanism 5, for a suitable length of time, after which its contents are dumped into the hopper 8, from which they will be fed by feeder 9, through chute 10 and spout 29, into the adjacent end of drum 11, which drum is suitably rotated as described above. It being understood that the speed of rotation of the drum will be sufficiently slow to enable thorough and complete treatment of the material before being discharged from the opposite end of the drum. As the drum rotates the material is agitated by being turned over and over, and dropped from the sides of the drum to its lower portion, which continued operation, due to the helical formation of flights 12, will simultaneously with the agitation and mixing of the hydrate, carry the same towards the delivery end 31 of the drum, and by the time the product reaches the latter end, it will be thoroughly mixed and sufficiently cooled to permit of the same being bagged.

It is of importance to note that the operation of drum 11 differs very materially from the ordinary spiral conveyer, the function of the latter being merely to push the materials longitudinally of the conveyer. In my combined mixer and conveyer, the material is as explained above very completely and thoroughly mixed, by being carried circumferentially with the drum as it rotates, until the material reaches a point at which it will drop downwardly to the lower portions of the drum, and be simultaneously worked forwardly toward end 31 of the drum by the spiral arrangement of flights 12.

By this arrangement the time that would otherwise be required for the treatment of the material in the primary mixer P, is very greatly lessened, and the latter may be kept more continually in operation and more frequently charged, due to its contents being dumped at shorter intervals into hopper 8, and their more effective treatment, comprising simultaneous mixing, cooling and con-

veying of the same in the secondary mixing device S, the operation of which, as will readily be understood, can be carried on simultaneously with the operation of primary mixer P.

It will thus be seen that I have provided a hydrating apparatus, the capacity of which is more than double that of the primary mixing device P, considered alone, and that I 10 am enabled to more thoroughly and completely mix the materials being treated, and simultaneously therewith cool and convey them to a point for bagging; all of these operations being carried out without the escape of lime dust or other disagreeable materials, to the surrounding neighborhood, as a result of which my apparatus can be successfully and satisfactorily operated within the city limits, or in more or less congested neighborhoods.

While I have described my apparatus as especially adapted for hydrating lime, I desire it to be understood that the same is susceptible of treatment of other materials, in 25 which the objects to be attained are more or less similar to those pointed out above. Also while I have illustrated a preferred embodiment of my invention, I desire the same to be understood as illustrative only and not as 30 limiting the scope of my invention.

Having now described my invention, I claim:

1. In lime hydrating apparatus, a primary mixing mechanism adapted to receive lime and water in predetermined quantities and mix the same, means to periodically deliver to said mechanism predetermined quantities of lime, means to periodically deliver to said mechanism predetermined quantities 35 of water, a secondary mixing apparatus for thoroughly completing the mixing of the said materials, said secondary mixing apparatus comprising an elongated drum having means for repeatedly agitating the material being treated and moving it from one end of the drum to the other, said means comprising helical flights extending substantially the length of the drum, and mechanism for rotating said drum, and means 45 for controlling the delivery of the material from the primary to the secondary mixer.

2. In lime hydrating apparatus, a primary mixing device adapted to receive a batch of lime and water in desired proportions, a

hopper below said mixing device adapted to 55 receive the contents thereof after treatment therein, a combined conveyer and finishing device at a lower level than the primary device, into which the material passes from the hopper, said last mentioned device comprising 60 an elongated rotatable drum having on its interior means for simultaneously agitating and moving longitudinally of the drum said material being treated.

3. In lime hydrating apparatus, a primary 65 mixing device adapted to receive batches of lime and water in desired proportions, a hopper below said mixing device adapted to receive the contents thereof after treatment therein, a combined conveyer and finishing device at a lower level than the primary device, into which the material passes from the hopper, said last mentioned device comprising 70 an elongated rotatable drum having on its interior means for simultaneously agitating and moving longitudinally of the drum said material being treated, and means for rotating said drum, to cause the material to be advanced.

4. In lime hydrating apparatus, a primary 80 mixing device, a combined conveyer and finishing device, and a connecting passageway between said parts, said conveyer and finishing device comprising a drum having a continuous flight arranged helically along the 85 interior thereof, said flight being of less width than the radius of the drum, and closed means into which said drum discharges its cooled and thoroughly mixed contents, to be bagged without substantial 90 escape of dust, means being provided around the drum where it enters the said closed means to entirely close the opening between the two.

5. In lime hydrating apparatus, a primary 95 mixing device, a weighing device for introducing a known quantity of lime into said primary mixing device, a water supply and sprinkling device for adding a desired quantity of water to the lime in said primary mixing device, a hopper below said mixing device to receive the contents thereof, and a combined conveyer and finishing device into which said hopper discharges.

In witness whereof, I hereunto subscribe 105 my name to this specification.

HUGH MISCAMPBELL.
